US00D768422S

(12) **United States Design Patent** (10) **Patent No.:** **US D768,422 S**
O'Neal et al. (45) **Date of Patent:** **** Oct. 11, 2016**

(54) **FOOT END SIDERAIL**

(71) Applicant: **Hill-Rom Services, Inc.**, Batesville, IN (US)

(72) Inventors: **Todd P. O'Neal**, Fairfield, OH (US); **Robert A. Bossingham**, Rushville, IN (US)

(73) Assignee: **Hill-Rom Services, Inc.**, Batesville, IN (US)

(**) Term: **14 Years**

(21) Appl. No.: **29/499,165**

(22) Filed: **Aug. 12, 2014**

(51) LOC (10) Cl. **06-06**

(52) U.S. Cl.

USPC **D6/718.3**

(58) **Field of Classification Search**

USPC D6/382-384, 718, 718.3; D24/183-185

(57) **CLAIM**

The ornamental design for a foot end siderail, as shown and described.

DESCRIPTION

FIG. 1 is a top front perspective view of a foot end siderail showing our new design;

FIG. 2 is a front elevation view of the foot end siderail of FIG. 1;

FIG. 3 is a rear elevation view of the foot end siderail of FIG. 1;

FIG. 4 is an end elevation view of a first end of the foot end siderail of FIG. 1;

FIG. 5 is an end elevation view of a second end of the foot end siderail of FIG. 1;

FIG. 6 is a top plan view of the foot end siderail of FIG. 1;

FIG. 7 is a bottom plan view of the foot end siderail of FIG. 1; and,

FIG. 8 is a top rear perspective view of the foot end siderail of FIG. 1.

The broken lines shown in the figures depict environmental subject matter and form no part of the claimed design.

1 Claim, 4 Drawing Sheets
